UNITED STATES PATENT OFFICE.

GEORGE L. BUCK, OF STEWARTSVILLE, MISSOURI.

DESIGN FOR A HIP-TERRET.

SPECIFICATION forming part of Design No. 20,479, dated January 13, 1891.

Application filed July 17, 1890. Serial No. 359,340. Term of patent 7 years.

To all whom it may concern:

Be it known that I, GEORGE L. BUCK, a citizen of the United States, residing at Stewartsville, in the county of De Kalb and State 5 of Missouri, have invented and produced a new and original Design for Hip-Terrets or Line-Supports for Harness, of which the following is a specification, reference being had to the accompanying drawings, forming part 10 thereof.

Figure 1 is a plan view of a terret, showing my design. Fig. 2 is a side elevation of the same, and Fig. 3 is a perspective view of the terret.

15 The leading feature of my design consists in a peculiarly-curved metallic bar, which when viewed in side elevation, as in Fig. 2, presents a flat base curved upwardly at each end, then inwardly, and on a line approximately parallel to the base, the free ends, which do not meet, presenting the forms of two adjacent oppositely-turned convolutes.

20 A is the base of the terret, which is substantially flat or straight for the main portion of its length.

B indicates the end curves, which are true semicircles, and C indicates the upper portions of the terret, which are in the main flat and approximately parallel with the base A.

The letter D indicates the extremities of the 30 terret, which are bent into the form of two adjacent and oppositely-turned convolutes, with a space between the coils somewhat wider than the thickness of the lines or reins to be held.

35

What I claim is—

The design for a hip-terret, as herein shown and described, the same comprising a flat or straight base with semicircular ends, the upper portions approximately parallel with the 40 base, and the adjacent extremities shaped in the form of reversely-turned convolutes, substantially as set forth.

GEORGE L. BUCK.
